UNITED STATES PATENT OFFICE.

HOWARD W. MATTHEWS, OF LANSDALE, PENNSYLVANIA, ASSIGNOR TO DEXDALE HOSIERY MILLS, OF LANSDALE, PENNSYLVANIA, A CORPORATION OF PENNSYLVANIA.

YARN-CLEANING DEVICE.

Application filed July 17, 1926. Serial No. 123,083.

This invention relates to yarn cleaning devices useful more particularly in connection with winding machinery to remove dirt, loose lint, burs, slugs, surface knots, etc., from yarns, thereby to preclude imperfections in the fabrics subsequently knit or woven from such yarns.

In the usual types of winding machines, a great number of yarns are spooled at one time, thus necessitating employment of a corresponding number of cleaning devices which require frequent attention to keep the yarn traversing slots free of accumulations tending to clog them. It is toward facilitating such cleaning and preventing unnecessary loss of time that my invention is in part directed, and this desiderata I attain by provision of "slug catcher blocks" which are slidably retained under friction in "holders" for convenience of ready and quick withdrawal without entailing complete removal of the devices from the winding machine.

The present invention is further concerned with structural improvements in the catcher blocks themselves, whereby they may be adapted to clean yarns of different gages. This end I secure by use, between two similar block components, of interchangeable shims, and by employment of suitable means to detachably secure the parts together.

With reference to the drawings herewith, Fig. I is a perspective view of a yarn cleaning device conveniently embodying my invention.

Fig. II is a horizontal section of the structure showing the block and its holder; and

Fig. III is a detail section taken as indicated by the arrows III—III in Fig. II.

As herein depicted, the device comprises a bracket-like member 9 with a shank 10 whereby it may be conveniently attached to the winding machine. The member 9 is furthermore formed with a head 12 which is recessed at 13 to serve as a holder for the slug catcher block comprehensively designated 14. This block 14 is slit longitudinally, as shown at 15, to provide the cleaning passage or slot for traverse of the yarn indicated by the letter Y in Fig. I, said yarn being guided to a centralized position in the slot by eyes 16, 16 adjustably set in integral lugs 17, 17 above and below the head or holder 12.

From Figs. II and III it will be noted that the block 14 comprises two components 18, 19 which are exact duplicates, and which are beveled as at 20, 20 to jointly provide an easy approach to the yarn traversing slot 15 for the purposes of ready threading. In accordance with my invention, the gage or width of the slot 15 is determined by a shim 21 interposed between the component parts 18, 19 at one end. As a convenient means to detachably secure the parts 18, 19 together, and to permit interchange of shims 21, I may employ screws 22 which pass through registering clearing apertures in the component 18 and shim 21, and take into the component 19. With this arrangement, the block 14 may obviously be adapted for cleaning yarns of different gages, simply by substitution of shims 21 of proper thickness.

To determine its proper allocation in the holder 12, the block 14 is provided with integral longitudinally-flanking ridges 23, 23 designed to engage corresponding open grooves 24, 24 at opposite sides of the recess 13; and its retainment against displacement is insured by a bowed spring 25 which occupies one of the aforesaid slots 24, and exerts frictional pressure upon the corresponding ridge 23 of said block 14. The spring 25 is anchored at 26 in the member 9, and its free end is curled to the form of a loop 27 whereby it may be grasped by one hand for easing of the pressure upon the block 14 incidentally to removal of the latter with the other hand.

By the described construction and arrangement it will be seen that the blocks of a number of such devices may be quickly withdrawn—and substitution effected—without necessitating complete removal of such devices from the winding machine nor interfering with continuous operation of the latter.

Having thus described my invention, I claim:

1. A yarn cleaning device comprising a bracket-like member with a recessed head having opposed slots, a catcher-block embodying two similar component parts having flanking ridges adapted to slidably fit the slots aforesaid, a shim interposed between the block components to determine the gage of the cleaning slot, means securing the block components and shim rigidly together.

with capacity for ready disassembling to enable interchange of shims and accommodation of the device to yarns of different gage, and flexible means co-operative with the 5 catcher-block in one of the above defined grooves to retain it against displacement.

2. A yarn cleaning device comprising a bracket-like member with a recessed head having opposed co-planar slots at right 10 angles thereto, a catcher-block embodying two similar component parts having flanking ridges adapted for sliding frictional fit in the head slots aforesaid, a shim interposed between the block components to determine 15 the gage of the cleaning slot, means securing

the block components and shim rigidly together with capacity for ready disassembling to enable interchange of shims and accommodation of yarns of different gage, and a bow-spring reposing in one of the above 20 named slots with its inner end anchored in the recessed head and its outer end formed into a grasp loop, said spring engaging the adjacent flanking ridge of the catcher-block to effectively retain the same against displacement. 25

In testimony whereof, I have hereunto signed my name at Lansdale, Pennsylvania, this 15th day of July, 1926.

HOWARD W. MATTHEWS.
